UNITED STATES PATENT OFFICE

WILLIAM H. LOYTE, OF SWAMPSCOTT, MASSACHUSETTS

ELECTRICALLY OPERATED KEY CONTAINER

Refile for abandoned application Serial No. 261,116, filed March 12, 1928. This application filed January 20, 1930. Serial No. 422,242.

This application is a refile of my abandoned application, Serial Number 261,116, filed March 12, 1928.

My invention comprises a device which when in use as hereinafter described provides a convenient receptacle for the key to a building provided with a sprinkler system for the prevention of fire, so that the key is readily available for opening the door of the building in case of fire.

I provide the mechanism illustrated in the accompanying drawings in which Figure 1 shows the key container; Figure 2 is a front view showing the relay latch in engagement with tubes, and showing diagrammatically the electrical connections with sprinkler circuit and police alarm circuit; Figure 3 is a perspective view of the mechanism at the back of the device; Figure 4 shows position of device in relation to wall of building; Figure 5 is a detail showing a form of the cover or cap; Figure 6 is a detail in section showing relative sizes of latch and lateral slots in the tubes, relative positions of the slots in relation to each other and the pin, also relative positions of contact parts at rear ends of the tubes.

I provide a plate 1 upon which the parts of my device are disposed. A long tube 2 projects through and is perpendicular to plate 1. Tube 2 is long enough to project through the door casing 3 of a building to the outside thereof when the apparatus is positioned as hereinafter described. Tube 2 is open at both ends and is held in position by means of a bracket 4 to which the tube is fastened by screws 5. In tube 2 is a lateral slot 6 and opposite the lateral slot is a pin 7 which projects into the tube. A post 8 is immovably mounted on bracket 4 by means of nut 9 and projects a short distance into tube 2, being centered therein. Within tube 2 and movably mounted on post 8 is a core 10 of wood or other non-conductive material. A nut 11 holds core 10 on post 8. A cup shaped piece of metal 12 is affixed to core 10 so that the open end 13 of the cup 12 is towards bracket 4. A helical spring 14 is mounted on post 8 and is in contact with and normally exerts pres-

sure on bracket 4 and cup 12. Affixed to plate 1 and passing therethrough is a contact stud 15. Affixed to contact stud 15 is a strip of contact metal 16 which is in contact with bracket 4 at 17. Affixed to plate 1 and passing therethrough is a contact stud 18. Affixed to stud 18 is a piece of contact metal 19, the free end of which 20 is near the open end 13 of metallic cup 12. A tube 21 closed at one end 22 and somewhat shorter than tube 2 is movably mounted in tube 2 with its open end 23 projecting inward and in contact with core 10. Near open end 23 of tube 21 is a lateral slot 24. Opposite slot 24 and extending from the open end 23 of tube 21 towards its closed end 22 to a position slightly beyond lateral slot 24 is a longitudinal slot 25. I provide a latch 26 which is pivotally mounted on a pivot 27 so that one end 28 of the latch may enter slot 6 in tube 2. A helical spring 29 affixed at one end to post 27 and engaging latch 26 exerts pressure on the latch and normally holds end 28 of the latch in slot 6. I provide a relay 30 having a striker 31, the free end of which is in contact with end 32 of latch 26 but normally exerting no pressure thereon. Wires 33 and 35 connect contact studs 34 and 36 of relay 30 with wires 39 and 40, respectively, of the electric circuit which operates fire extinguishing sprinkler system indicated by letter S in Figure 2 of the drawings.

The operative position of my invention is preferably on or near the door frame and is affixed to the inner side of the building in any suitable manner, as by screws or bolts. Tube 2 projects through the wall to the outside of the building and I provide a removable cap 41 for covering the ends of the tubes.

When the device is set up it is made ready for use in the following manner: The door key is placed in tube 21. The open end of the tube is then inserted in tube 2 from outside of the building and tube 21 is turned until longitudinal slot 25 engages pin 7 in tube 2. Tube 21 is then pressed into tube 2 until lateral slot 24 in tube 21 is positioned parallel with and adja-

cent to lateral slot 6 in tube 2. Thereupon the pressure exerted on latch 26 by spring 29 forces locking end 28 of the latch into lateral slot 24 so that tube 21 is locked in tube 2 with closed end 22 of tube 21 flush with the outer end of tube 2. To attain this locked position spring 14 has been made to contract. It will be found that pin 7 rests in longitudinal slot 25 at a short distance from the inner end of the slot. After tube 21 has been locked in tube 2 as described, it will be found that pressure on closed end 22 of tube 21 will cause tube 21 to move farther into tube 2 until open end 13 of metallic cup 12 touches contact metal 19 at 20, this movement being made possible by the position of pin 7 with reference to the inner end of longitudinal slot 25 which permits the slight additional movement required to make such contact.

The operation of my device is as follows: When fire in the building causes the sprinkler system to operate by means of the electrical system, the electric current passes through the relay 30 causing relay striker 31 to exert pressure on end 32 of latch 26 and this pressure causes the locking end 28 of latch 26 to withdraw from lateral slots 6 and 24, thus releasing tube 21. Thereupon expansion of spring 14 forces closed end 22 of tube 21 beyond end of tube 2 on outside of building. Upon removal of cap 41 tube 21 may be pulled out of tube 2, the key obtained and the door of the building opened therewith, thus avoiding damage to property and delay in reaching the fire due to forcing an entrance as now practiced. The key may be returned to the container and the device made operative again as described.

To prevent theft of the key from the container 1 I make tube 21 of hardened steel with its closed end 22 extra thick. Tube 21 being fitted into tube 2 and locked as described, the only means for getting access to the key would be by boring through end 22 of tube 21 which would involve pressure on the end of tube 21. In order to give notice of attempts to remove the key, studs 15 and 18 are connected by wires 37 and 38 with an alarm, as A, operated by a battery B, the alarm being on the outside of the building or in the nearest police station or in both places. If then an attempt is made to steal the key, pressure on end 22 of tube 21 forces open end 13 of metallic cup 12 into contact with metallic piece 19 at 20, closing the electric circuit through battery B and alarm A, causing the alarm to ring, but not releasing tube 21 and the key. For protection I enclose the entire device in a box C of suitable size, shown in cross-section in Figure 4.

My device may be used with or without the parts pertaining to the giving of notice

of attempted theft and be within the scope of my invention.

While I have described as my preferred construction a metallic cup 12 and contact strips 16 and 19, I do not desire to limit myself to such construction but I have in mind to claim the substitution of conductive material of any shape that will make my device operative to be within the scope of my invention. Also, while I have described a relay striker as acting upon the latch to open it, I do not desire to limit myself to that mode of operation, but claim, for example, the operation of the latch through a rigid connection between it and the armature of the magnet, to be within the scope of my invention.

Having described my invention, what I claim is:

1. In a device of the class described, a plate, a tube mounted on the plate, open at both ends and long enough to project from the plate through the door casing of a building to the outside of the building, a bracket mounted on the plate and means for fastening the tube to the bracket, a lateral slot in the tube, a pin projecting laterally into the tube, a post immovably mounted on the bracket and projecting into the tube, a core of nonconductive material within the tube and movably mounted on the post, contact metal affixed to the core and positioned between the core and bracket, a helical spring mounted on the post and normally exerting pressure on the bracket and contact metal, a contact stud passing through the plate, contact metal operatively connecting the stud and bracket, contact metal affixed to the plate and positioned between the first mentioned contact metal and the bracket, a contact stud passing through the plate and the last mentioned contact metal, a tube closed at one end and movably mounted in the first mentioned tube and having its open end projecting into said first mentioned tube and in contact with the core therein, a lateral slot near the open end of the inner tube, a longitudinal slot extending from the open end of the inner tube and diametrically opposite said lateral slot, a latch pivotally mounted on a post so that the end of the latch may enter the lateral slots in the tubes, a spring on the post and normally exerting pressure on the latch so as to hold it in the slots, an electric relay, means for exerting pressure on the latch and withdrawing its latching end from the slots when the relay is electrically operated, wires connecting the contact studs of the relay with the electric circuit which operates a fire sprinkler system, and wires which connect the contact studs on the plate with a burglar alarm, as described.

2. In a device of the class described, a plate, a tube open at both ends, mounted on

the plate and long enough to project from the plate through the door casing of a building to the outside of the building, a bracket mounted on the plate and means for fastening the tube to the bracket, a lateral slot in the tube, a pin projecting laterally into the tube, a core within the tube and movably mounted on a post, a helical spring mounted on the post and normally exerting pressure on the bracket and core, a tube closed at one end and movably mounted in the first mentioned tube and having its open end projecting into the first mentioned tube and in contact with the core therein, a lateral slot near the open end of the inner tube, a longitudinal slot extending from the open end of the inner tube and diametrically opposite said lateral slot, a latch pivotally mounted on a post so that an end of the latch may enter the lateral slots in the tubes, a spring on the post and normally exerting pressure on the latch so as to hold the locking end thereof normally in the slots in the tubes, an electric relay, means for exerting pressure on the latch and withdrawing its locking end from the slots when the relay is electrically operated, and wires connecting contact studs on the relay with the electric circuit which operates a fire sprinkler system, as described.
